The ornamental design for a cycling computer mount, as shown and described.

DESCRIPTION

FIG. 1 is a topside perspective view of a cycling computer mount showing our new design.

FIG. 2 is a top plan view thereof.

FIG. 3 is a bottom plan view thereof.

FIG. 4 is a left side view thereof.

FIG. 5 is a right side view thereof.

FIG. 6 is a front elevation view thereof.

FIG. 7 is a back elevation view thereof.

FIG. 8 is another topside perspective view thereof, where the environmental computer is not shown;

FIG. 9 is a top plan view thereof; and,

FIG. 10 is a right side view thereof.

The broken lines shown in the drawings represent visible environmental structure or unclaimed portions of the structure of the cycling computer mount, and form no part of the claimed design. The shade lines in the drawings show contour and not surface ornamentation.
